UNITED STATES PATENT OFFICE.

WILLIAM CUTLER, OF EDGBASTON, BIRMINGHAM, ENGLAND.

FORCING FRAME OR INCLOSURE FOR HORTICULTURAL OR OTHER PURPOSES.

958,956.

Specification of Letters Patent. Patented May 24, 1910.

Application filed October 4, 1909. Serial No. 520,997.

To all whom it may concern:

Be it known that I, WILLIAM CUTLER, a subject of the Kingdom of Great Britain, residing at 10 Wheeleys road, Edgbaston, 5 Birmingham, England, have invented certain new and useful Improvements in Forcing Frames or Inclosures for Horticultural or other Purposes, of which the following is a specification.

10 This invention relates to forcing frames and inclosures for horticultural or other purposes and refers particularly to those frames in which the lower portion of the light rests in grooves formed in the base frame while the upper portions butt against a longitudinally disposed member, the present improvements comprising means whereby the lights may be retained within supports upon the frame when such lights are 20 out of use.

Reference may be had to the appended explanatory sheet of drawings upon which—

Figure 1 is a general perspective view showing the frame closed. Fig. 2 shows 25 the frame in the open position. Fig. 3 is a sectional view upon the line 1—2 of Fig. 1.

In a convenient embodiment of this invention the forcing inclosure is bounded by a base frame A of rectangular configuration, 30 and which may preferably consist of single boards or planks a' of woodwork secured at the corners in any suitable manner and forming the medium whereby the inclosure is protected from wind and such like atmospheric influence. The said rectangular base frame A is provided centrally at each extremity with a standard or upright post a² which posts are adapted to carry a central longitudinal beam a³ forming the apex of 35 the glazed top or roof of the inclosure. The upper edges of the wood-work a' forming the rectangular frame A are grooved at a⁴ for the reception of the edges of the glass a⁵ and the sides a⁶ of the vertical standards a² are likewise grooved so that by the appropriate insertion of four triangular panes 40 of glass a⁷ the extremities of the inclosure are effectively glazed. Rectangular or square panes B of glass are then disposed 45 obliquely with their lower edges resting in the grooves a⁴ within the longitudinal base members a' of the frame A, the said obliquely disposed panes B abutting one with

the other and also with the hypotenuses of the triangular panes a⁷ to completely cover 55 the inclosure. The central longitudinal beam a³ may be of cross section suited to the efficient support of the upper edges of the oblique panes B, and may have a protector cap b' or longitudinal cover of metal, embracing the upper edges of the oblique panes on both sides, sufficient play being allowed between the panes B and the cover b' to allow of their lower edges being lifted out of the base grooves a⁴ in the process of their 60 removal.

At positions substantially corresponding with the abutting edges of the oblique panes, vertical spacing members b² are secured externally to the side members a' of the base 70 frame A, and similar members b² are also provided at the extremities of said side members, outside strips C' being connected to the vertical spacing members and forming pockets for the panes B, such vertical members 75 being grooved for the reception of the panes of glass B when not covering the roof of the frame as in Fig. 2. Suitable stops or supports C are secured to the side members of the base frame at positions intermediate 80 to the vertical members b², said stops C having for their purpose to form bases for the panes of glass B when in the out-of-use position shown in Fig. 2. It will be obvious that the panes of glass B when in such out 85 of use position may extend considerably above the top edges of the base frame A and thereby effect a partial protection of the inclosure.

By virtue of the provision whereby the 90 panes are satisfactorily installed in the frame both when the in-use and out-of-use position not only is the possibility of breakage of the glass very materially reduced, but the entire frame is adapted for removal from one position to another with considerable facility.

Having now described my invention, I declare that what I desire to secure by Letters Patent is:—

A forcing frame comprising a base having 100 its top edges grooved, standards at two opposite sides of the base having their sides grooved, a longitudinal beam connecting the upper ends of the standards together, an obliquely disposed translucent cover with its 105 bottom edge resting in the grooves of the

base and its top edge resting against the longitudinal beam, a protector cap for the longitudinal beam embracing the top edge of the cover, end covers held in the grooves 5 of the base and standards and engaging the top cover, and vertical pockets in the base for the top cover.

In witness whereof I have hereunto set my hand in the presence of two witnesses.

WILLIAM CUTLER.
